UNITED STATES PATENT OFFICE.

EDWARD MATTHEWS, OF DENVER, COLORADO, ASSIGNEE OF ONE-HALF TO LEWIS E. LEMEN, OF DENVER, COLORADO.

VEHICLE-SPRING.

1,225,458.

Specification of Letters Patent.

Patented May 8, 1917.

Application filed May 22, 1916. Serial No. 99,627.

To all whom it may concern:

Be it known that I, EDWARD MATTHEWS, a citizen of the United States, residing in the city and county of Denver and State of Colorado, have invented certain new and useful Improvements in Vehicle-Springs; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in springs for vehicles, and particularly to the type employed in connection with automobiles. My object is to produce a spring of this character in which vibration is reduced to the minimum, and at the same time permit the spring sufficient sensitiveness to respond quickly and easily regardless of the load carried by the vehicle. In fact, by virtue of my construction the spring really acts as a shock absorber, and as the vibration is materially reduced at this point crystallization of the spring leaves is prevented and the life of the spring greatly increased.

In order to produce the above named results I make my spring in two sections, the said sections being separated by a block composed of wood or other nonvibrating material. These elements are securely fastened together and attached to the axle of the vehicle by means of H-bolts, and a particular feature of this fastening means is that the leaves comprising the lower section of the spring are held firmly together and secured to the axle independently of the block and leaves forming the upper section.

I wish it understood, however, that I do not limit myself to the specific fastening means disclosed, since I am aware that other suitable means may be employed without departing from the spirit of my invention.

Another important feature of my invention consists in pivotally connecting the extremities of the lower section with the frame of the vehicle and movably connecting the extremities of the upper section with said lower section.

Having briefly outlined my improved construction, I will proceed to describe the same in detail, reference being made to the accom-

panying drawing, in which is illustrated an embodiment thereof. In this drawing—

Figure 1 is a view in elevation of my improved spring, showing the same secured to the front end of a vehicle frame.

Fig. 2 is a similar view showing the spring under tension, or its position when weighted down.

Fig. 3 is a cross section of the spring taken on the line 3—3, Fig. 2, on an enlarged scale.

Fig. 4 is a detail view of the central portion of the spring partly in section.

The same reference characters indicate the same parts in all the views.

Let the numeral 5 designate my improved spring in its entirety which is composed of upper and lower sections 6 and 7 respectively. The lower section 7 comprises a series of spring leaves of ordinary construction, the said leaves being secured to the axle 8 of the vehicle by means of H-bolts 9, the cross pieces 10 of the said bolts engaging the top leaf of the section and the side portions of the bolts below the cross pieces 10 embracing the opposite sides of the said section, the lower extremities of these side portions being threaded and adapted to project through perforations 12 formed in the axle. Nuts 13 are applied to these threaded extremities of the bolts, whereby the leaves 85 of the section 7 are securely held together and fastened to the axle.

A block 14 composed of non-vibrating material, preferably wood, is mounted on top of the section 7, the under surface of the said block being provided with recesses 15 into which fit the cross pieces 10 of the H-bolts. Upon this block is placed the upper section 6 of the spring, this section being preferably composed of a less number 95 of leaves than the lower section 7.

The upper side portions of the H-bolts 9 above the cross pieces 10 embrace the opposite sides of this upper section, and their extremities are reduced and project through 100 perforations formed in a reinforcing plate 16 which is mounted upon the uppermost leaf of the section 6. Cross pieces 17 are fitted over the upper extremities of the H-bolts and are adapted to rest upon the 105 plate 16, said cross pieces being held securely in place by nuts 18, which are applied to the H-bolts' extremities, the latter being

threaded for this purpose. These nuts when screwed tightly in place, besides securing the leaves of the upper section 6 together, practically form an integral construction including both sections 6 and 7, the plate 16 and the interposed non-vibrating block 14. These said elements are further secured together by means of a bolt A, the head of which fits into a recess B formed in the axle and whose shank extends upwardly through both spring sections, the block and the plate 16, the upper extremity of the bolt having a nut C screwed thereon which tightly engages the said plate 16.

15 It should, however, be especially noted in this connection that the leaves comprising the lower section 7, are fastened tightly together and attached to the front axle 8 independently of the means for securing the plate 16, block 14 and leaves comprising the upper section 6.

One extremity of the section 7 is pivotally connected with one extremity of the vehicle frame 4 as disclosed at 19, while the other extremity of the said section is pivotally connected as shown at 20, with the lower extremity of a link 21, the opposite extremity of which is pivotally connected with a bracket 22 secured to the under surface of the frame 4. The opposite extremities of the section 6 are each pivotally connected with a pair of links 23 which, after the said section is forced downwardly from its natural position (disclosed by dotted lines in Fig. 1), will straddle the end portions of the lower section 7, after which the lower extremities of the links 23 are connected by pins 24 which are adapted to engage the said section 7, whereby the extremities of the upper section are movably connected with the end portions of the lower section.

By reason of the block interposed between the spring sections and the manner in which these sections are secured to the axle and frame of the vehicle, the upper section 6 can be so arranged that it will act as a sort of buffer, or, in other words, will, to a certain degree, counteract the rebound of the

lower spring section 7, thereby absorbing a great portion of the shock incident thereto, 50 and thus reducing the vibration to the minimum.

Attention is called to the fact that my improved spring may be employed as the upper or lower half of an elliptical spring, 55 or one of my springs may be employed as the lower half and one as the upper half of such a spring, and, furthermore, it may constitute the lower member of a three-quarter elliptical spring.

60 Also my spring may be mounted upon either the front or rear axle of the vehicle.

Having thus described my invention, what I claim is,—

1. A vehicle spring composed of upper 65 and lower sections, a block interposed between the said sections midway of the extremities of the latter, H-bolts for securing the central portion of the spring to the axle of the vehicle, the upper and lower arms of 70 said bolt embracing the upper and lower sections respectively, and cross pieces of the said H-bolts adapted to bear upon the upper surface of the lower section whereby the leaves comprising the latter are independently secured in place.

2. A vehicle spring composed of upper and lower sections, a block interposed between the said sections midway of the extremities of the latter, H-bolts for securing 80 the central portion of the spring to the axle of the vehicle, the upper and lower arms of said bolt embracing the upper and lower sections respectively, and cross pieces of the said H-bolts engaging recesses formed in 85 the said block and adapted to bear upon the upper surface of the lower section whereby the leaves comprising the latter are independently secured in place.

90 In testimony whereof I affix my signature, in presence of two witnesses.

EDWARD MATTHEWS.
